UNITED STATES PATENT OFFICE

CARL SCHUSTER, OF BELLEVUE, PENNSYLVANIA, ASSIGNOR OF ONE-HALF TO
CHRISTIAN N. BERGMANN, OF PITTSBURGH, PENNSYLVANIA.

CONDUCTOR-POST.

1,086,623.

Specification of Letters Patent.

Patented Feb. 10, 1914.

Application filed January 10, 1912. Serial No. 870,432.

To all whom it may concern:

Be it known that I, CARL SCHUSTER, a citizen of the United States, residing at Bellevue, in the county of Allegheny and State of Pennsylvania, have invented certain new and useful Improvements in Conductor-Posts, of which the following is a specification.

My invention relates to improvements in conductor posts for knife switches and similar electrical apparatus, and it has for its object to provide a post of this class composed of a plurality of comparatively thin flat conductor bars and intervening similar spacers, fixedly connected together and provided with, or adapted to be provided with, a surrounding fixedly attached frame, for mounting and attachment to a supporting insulating base.

One preferred form of the invention is illustrated in the accompanying drawings in which:

Figure 1 is a view of a knife switch in side elevation embodying my invention. Fig. 2 is a vertical sectional view on the line II. II. of Fig. 1. Fig. 3 is a sectional detail view on the line III. III. of Fig. 1. Fig. 4 is a similar view illustrating a modified construction. Fig. 5 is a perspective view showing the conductors and spacers comprising the post assembled and riveted together. Fig. 6 is a similar view showing the post with the holding frame attached.

The post is generally similar in construction to that illustrated in my prior application, Serial No. 506054, filed July 6, 1909, adapted to transmit high ampere currents from one side of a switch board or base to the other, and is usually used in combination with bus bar and switch connections and the like.

A particular object of the present invention is to provide a construction in which continuous flat conductor bars are closely and compactly associated with intervening spacers in fixed parallel contacting relation; and, further, to provide securing means for this purpose which may be formed in part by the holding frame or mounting, and in part by independent fastening means engaging the conductor bars and the spacers beyond the mounting. Such independent fastenings constitute means for holding the parts together as a unitary structure independent of the holding frame, and whereby

such parts may be handled and shipped as a unit independently of said frame. They also positively hold the bars and spacers against spreading or edgewise movement within the base. Also, whereby an embracing frame is fixedly connected with the entire construction so as to provide a unitary structure which is easily adapted to incorporation with the other elements of the equipment.

The construction of the post, as made, also greatly contributes to and facilitates the operation of assembling the parts.

In the drawings, 2 is the insulating base of a switch board or other similar construction, through which the composite post extends, two such posts being usually employed whereby to provide terminals at one side of the base for connection with the bus bar terminals 3, 4, and at the other side for the connecting switch blades 5, of well known construction.

Each post is substantially the same in construction, the non-essential difference being mainly in the knife blade receiving terminals.

The post is composed of a series of continuous conductor bars 6, suitably spaced apart to receive the ends of the strip members of the plural bus bars 3 or 4 at one side 80 of the base 2, and the ends of the switch blades 5 at the other side of the base. For the purpose of so spacing the bars 6, I employ a series of flat spacers 7. These may be of a length and so located as to correspond substantially to the combined thickness of the base 2 and the holding frame 8, or of greater or shorter length as desired, provided there is enough stock to provide for the holding rivets. These spacers are 90 similar to the conductors in every respect, but shorter, and as shown, may be of varying thickness to provide the desired space between each member of each pair of conductors, corresponding to the thickness of 100 the bus bar strips and switch blades, and of a slightly less width for separation of one pair of conductors from the next adjacent pair. The spacers are of the same width as the conductors and are flat and comparatively thin, and when the conductors and spacers are assembled, they fit tightly and compactly together.

In assembling the several conductors and spacers, the latter are interleaved and lo-

2 cated at the proper distance longitudinally of the conductors, and the combined structure is then clamped together by clamps engaging the sides of the outer conductors for 5 a distance indicated by the lines a, a , to b, b , Fig. 5. By this means, due to the intervening spacers, the assembled conductors and spacers are rigidly held immovably in the clamp, and rivets 9 are then passed through 10 all of the conductors and spacers, the heads being countersunk, flush with the outside surfaces, or rounded as preferred. The clamps are then removed and the frame 8 is placed around the assembled compacted 15 group and is also riveted thereto by rivets 10, preferably having countersunk heads flush with the outer surface. The entire post is thus solidly connected. Each pair of conductors is uniformly spaced apart. The 20 spacers are brought into tight intimate contact with the conductors. They extend for a distance longitudinally of them corresponding to the distance required for clearance of the clamps in placing the rivets and for giving enough body and backing for the rivets themselves. They also provide a solid body 25 and backing for the frame-securing rivets. As shown in the principal figures, they may be of a length to practically fill the spaces 30 between the conductors longitudinally for a distance equal to the combined thickness of the frame 8 and base 2. In other words, when the post is installed, the spacers extend through, or substantially through, the 35 insulating base as well as through the frame.

While good results may be had by extending the spacers sufficiently far to extend into or through the thickness of the base, it will be understood that the invention is not limited to such construction but that the holding action of the rivets will give the desired 40 stability with spacers of greater or less length.

An especial advantage of the construction 45 is in the increased conductivity of the post through its middle portion embraced by the base and frame, providing a substantially solid continuous post of ample cross section, thus greatly facilitating the transmission 50 of the current. A further advantage in the construction is that by extending the spacers through the base, the conductivity of the post is increased and heating of the several conductors 6, due to lack of ventilation in 55 the inclosed recess of the base, is prevented.

The frame 8 is secured to the base by screws or bolts 11 tapped into the under side of the frame or in any other suitable manner.

60 If desired, the spacers may be comparatively short, as indicated at 7^a, Fig. 4, of a length substantially corresponding to the thickness of the base 8^a provided there is enough stock for engagement of the primary holding rivets 9^a. Also, that a supple-

mental series of spacers 7^b may be inserted between the conductors 6^a and the conductors and spacers secured together by a plurality of rivets 9^b at any suitable location beyond the set of spacers 7^a. By this arrangement the elements of post are strongly and rigidly connected at two points in its length, and the spacing of the conductor terminals fixedly determined.

It will be observed that by my construction I provide for connection with the switch blades at one side and with the bus bars at the other side of the base, by a conducting post which is continuous from one side to the other, comprising laminæ of undiminished area and contact surface throughout and co-extensive with the area of the blade and bus bar surfaces. The several conductors of a single post, although separated, thus constitute a practically one-piece laminated post or bar.

The advantage of the construction arises from its high conducting capacity, avoidance of joints, heating, and loss of current, simplicity of construction, and ease of manufacture and equipment. The posts may readily be made as units, either with or without the frames, and readily handled, packed or shipped without danger of disturbance, thus easily maintaining their standard proportions, gages, etc.

What I claim is:

1. The combination with an insulating base, of a series of assembled flat conductor bars extending through said base, a series 100 of flat spacing strips interposed between the conductor bars and also extending through the base, a holding frame fixedly secured upon one side of the base and to the bars and to the spacing strips, and other fastening 105 means which fixedly secure the bars and strips to each other within the base inwardly and independently of and materially beyond and apart from the holding frame and its securing means, whereby to prevent spreading or edgewise movement of the bars or spacing strips within the base, substantially as described.

2. In a conductor post adapted to extend through a supporting base and to be secured thereon by a surrounding frame, a unitary series of thin flat conductors permanently spaced apart the one from the other by intervening flat separating spacers adapted to extend through the base when mounted thereon, 110 a holding and mounting frame, rivets fixedly connecting the frame, conductors and spacers at one end portion of the latter, and additional rivets fixedly holding the conductors and spacers together independent of 115 and inwardly beyond the frame, whereby to prevent spreading or edgewise movement of the bars or spacers within the base, substantially as set forth.

3. In a conductor post adapted to extend 120

through a supporting insulating base and to be secured thereon, a unitary series of thin flat conductors permanently spaced apart the one from the other by an intervening flat separating spacer adapted to extend through the insulating base when mounted thereon, a frame embracing the conductors and spacer, rivets extending through the conductors, spacer and frame and fixedly holding said parts together, and additional rivets fixedly holding the conductors and spacer together independent of and beyond the frame, at that portion which is adapted to extend through the base whereby to prevent spreading or edgewise movement of the bars or spacer within the base, substantially as set forth.

4. A composite conductor post composed

of series of alternating thin flat conductors and spacers in laminated arrangement, a surrounding mounting frame, rivets fixedly connecting the frame to the post, said spacers extending beyond the inner face of the frame, and additional rivets located inwardly beyond the inner face of the frame and near the opposite ends of the spacers, fixedly connecting the conductors and spacers tightly together, whereby to prevent spreading or edgewise movement of the bars or spacers, substantially as set forth. 30

In testimony whereof I hereunto affix my signature in the presence of two witnesses.

CARL SCHUSTER.
